UNITED STATES PATENT OFFICE

AXEL FOLKE CARLSON, OF CAMBRIDGE, MASSACHUSETTS, ASSIGNOR TO REECE SHOE MACHINERY COMPANY, OF BOSTON, MASSACHUSETTS, A CORPORATION OF MAINE

WELT SEWING MACHINE

Application filed March 31, 1928. Serial No. 266,420.

This invention relates to welt sewing machines and more especially to sewing machines known as the welt and turn machine, an example of which is the Reece welter in which the upper of a boot or shoe is stitched to the lip of the insole and to the welt strip. Machines of this type are exemplified by the J. R. Oliver Patents No. 1,599,431 of September 14, 1926, No. 1,712,517 of May 14, 1929 and No. 1,770,992 of July 22, 1930, and the earlier patents mentioned therein.

The general object of the present invention is to improve the operation of welt sewing machines, and especially to improve the mode of feeding, guiding and applying the welt. Other and further advantageous features of the present invention will be pointed out in the hereinafter following description of an illustrative embodiment thereof or will be understood to those conversant with the subject.

To the attainment of such objects and advantages the present invention consists in the novel welt sewing machine, and welt handling mechanism, and novel features of combination, arrangement, operation and structure herein illustrated or described.

In the accompanying drawings Fig. 1 is a right elevation of a sufficient part of a Reece welt sewing machine to illustrate in connection with the other figures, the principles of the present invention.

Fig. 2 is a partial front elevation of the characteristic portions of the mechanisms.

Fig. 3 is a vertical section looking from the right and taken on the line 3—3 of Fig. 2 or Fig. 4.

Fig. 4 is a vertical section looking from the front and taken on the line 4—4 of Fig. 3.

Similar reference numbers are applied to corresponding parts in the several figures of the drawings.

Referring to the drawings Fig. 1 shows a shoe in sewing position. Surrounding the last *l* is the insole *s* with its outturned lip *s'*, the shoe upper *u*, and the welt strip *w* being fed into place and attached by thread *t* to the upper and insole lip.

The machine frame may comprise the usual tall post 9 at the upper end of which is a

suitable head or frame including fore-and-aft frame walls 10 and 11, being the two usual frame walls, and giving support to the mechanism of this invention. The stitching shaft 12 is shown as turning in the walls 10 and 11 along with other usual bearings. The thread *t* usually comes from a waxpot at the rear, passing first to a thread wheel 13 around which the thread travels subject to the restraining action of a tension control or device 14. From the tension of thread passes to a take-up lever 15 and thence to the usual looper 16 operated to apply a loop of the waxed thread to the barbed point of the needle 17, the needle thus applying successive stitches to the work, while, between stitches the work is fed forwardly by the usual reciprocating feed point or device 18.

The shoe or work is shown as being held to position in contact against a bumper or work rest 19, which as usual may be yielding during one portion of each stitch cycle, but locked forwardly during the retraction of the needle. The work also bears against the welt guide 20 supported on a movable carrier 21 fulcrumed for example to swing about axle 22 supported in bearings 23 above the stitching point. The welt guide, like the work rest, is intended to be held yieldingly forward to the work during part of each cycle, but locked forward during the retraction of the needle. For this purpose a link 26 is shown extending from the lower end of the welt guide carrying lever 21 to a reciprocating slide 27, these parts being normally held yieldingly forward by a strong spring 28, shown illustratively as a plate spring upstanding from a fixed part of the machine frame. In order to lock forwardly these parts during the retraction of the needle any well known locking means may be employed, such as the wedging grip arm 30 corresponding with that shown in Patent 1,599,431, this being operated through a link or other connection 31 and allowed to be drawn rearwardly into wedging contact with the slide, at the proper points of time, by a spring 32. The work rest 19 may have similar control as in said patent.

It is sometimes desirable to operate the 100

welt guide 20 to have a slight rearward or retracting movement during each stitch cycle preferably immediately preceding the feeding period, the welt guide being retracted a short extent and then returned forwardly and restored to contact with the shoe as the feed motion ceases; this not merely reducing resistance and thus facilitating the feed movement, but tending also to advance the welt in operation for the feed movement and supply it with minimum drag during the feed movement. For this purpose the present invention shows the following novel and effective mechanism. The overhead axle 22 which carries the swinging welt guide carrier 21 is shown as a rock shaft supported in bearings 23. At a point considerably in advance of, or to the right of, the welt guide carrier, the rock shaft 22 is shown as carrying a rock arm 35, pinned to the shaft, and extending upwardly to where, at its upper end, it is formed with an arc shaped flange 36 concentric with the shaft 22. This arc member or flange 36 is one member of a device in the nature of a pawl and ratchet, without teeth but working by friction and gripping, the other member, which may be termed the pawl 37, being shown as engaged with a snug fit on the arc member, as best seen in Fig. 3, and having a corresponding conformation, so that normally there may be free relative sliding of the arc member through the pawl member during rocking movements of the rock shaft 22. The body of the pawl member 37 contacts at the underside of the arc member 36, while the pawl member has an overlying extension 38 contacting the upper side of the arc member. As seen in Fig. 4 the underlying and overlying parts of the pawl member are interconnected by metal extending vertically to the right of the arc member, and when assembled the parts may be confined in their illustrated position by a guard member or overhanging plate 39 attached to the portion 38 to the left of the arc member.

For the purposes of this invention the pawl member 37 may be substantially free or floating, without any fixed mounting, while a spring 40 is shown tending always to draw the pawl member rearwardly to the normal position indicated in Fig. 1. In those parts of the cycle when the pawl member is idle it is thus held rearward and inactive, while the arc member 36 rocks freely forwardly and rearwardly with the rock shaft carrying it.

At the points in the cycle however when the welt guide is to be retracted the pawl member 37 becomes active and cooperates with the arc member 36 to swing the rock lever 35 forwardly and thus swing rearwardly the welt guide. For the purpose of this operation the pawl member 37 is shown as having at its lower end a contact or head

41 adapted to be contacted and thrust forwardly by a finger or shoulder 42 extending upwardly from a sleeve 43 turning loosely on the axle 22. When the sleeve 43 is turned, as will be described, in a manner to throw forwardly the finger 42, this contacts and throws forwardly the contact head 41 of the pawl member 37. The immediate effect of the pressure of 42 against 41 is the gripping of the arc member 36 by the pawl member. This action will be understood from Fig. 3. The gripping is instantaneous and powerful. The consequence is that the continued forward movement of the finger 42 causes the forward swinging of the pawl member 37, the arc member 36 and the rock arm 35 carrying the latter. This rocks the axle 22 and retracts the welt guide for a proper distance, as described.

The rotating of the sleeve 43 for these purposes may be effected automatically by the following connections. Integral with the loose sleeve 43 is an upstanding rock arm 44 and at the upper end of this rock arm is a pivot 45, adjustable to vary the throw, connected by a rod 46 with a guide arm 47 having a fixed fulcrum 48 on the frame wall 11, the connecting rod having a cam stud or follower 49 running in a cam groove 50 of a cam disk 51 mounted on the operating or stitching shaft 12.

The parts are shown in the position at which the retraction of the welt guide is very shortly to occur, the stitching shaft turning counterclockwise in Fig. 1. By the inclined cam portion 52 the connecting rod 46 is thrown forward and this throws forwardly the rock arm 44 and the contact finger 42, which in turn operates through the pawl and ratchet device, as described, to draw rearwardly the welt guide; following which the cam portion 53 comes into effect to bring about a smooth easy return of the parts to normal; and it will be seen that in normal position the pawl actuating finger 42 is slightly out of contact with the pawl head 41, so that the pawl is in floating condition, held only by its spring and bearing rearwardly against a fixed stop 55.

In one aspect the disclosed improvement may be described as comprising the welt guide 20 mounted for movement transversely of the feed of the work, together with means for retracting and returning the welt guide in each stitch cycle, comprising a rock member, which may be the carrier 21, shaft 22, or arm 35, from which the welt guide takes its retracting motion, the concentric arc piece 36 which rocks with the said rock member, a gripping member 37 engaging or embracing slidably the arc piece, and timed means, the finger 42 along with its connections from the stitching shaft, arranged to thrust on said grip member so as to cause it to grip the arc 130

piece and thereby retract the welt guide in each stitch cycle.

There has thus been described a welt sewing machine embodying a welt guiding device constructed and operating in accordance with the principles of the present invention. Since many matters of combination, arrangement, operation and structure may be variously modified without departing from the principles of the invention, it is not intended to limit the invention to such matters except to the extent set forth in the appended claims.

What is claimed is:

1. In a welt sewing machine having means for feeding the work and for stitching the welt thereto, a welt guide mounted for movement transversely of the feed, and means for causing the retraction of the welt guide from the work in each stitch cycle and its return to the work, comprising a rock member through which the welt guide is given its retracting motion, a concentric arc piece rocking with said rock member, a rigid grip member having opposite portions engaging slidably with the outer and inner sides of said arc piece, and timed means to thrust on said grip member to cause it to tilt and thereby grip the arc piece and thereupon rock the arc piece and rock member.

2. In a welt sewing machine having means for feeding the work and for stitching the welt thereto, a welt guide mounted for movement transversely of the feed, and means for causing the retraction of the welt guide from the work in each stitch cycle and its return to the work, comprising a rock member through which the welt guide is given its retracting motion, a concentric arc piece rocking with said rock member, a grip member slideable freely upon said arc piece, a stop for the normal position of the grip member, a spring restraining the grip member and pressing it retractingly to the stop and timed means to thrust on said grip member to cause it to grip and rock the arc piece and thereby to retract the welt guide in each stitch cycle.

3. In a welt sewing machine having means for feeding the work and for stitching the welt thereto, a welt guide mounted for movement transversely of the feed, and means for causing the retraction of the welt guide from the work in each stitch cycle and its return to the work, comprising a rock member through which the welt guide is given its retracting motion, a concentric arc piece rocking with said rock member, a grip member engaging slidably with said arc piece, the grip member normally occupying a retracted position, timed means to thrust on said grip member to cause it to grip and rock the arc piece and thereby to retract the welt guide in each stitch cycle; means yieldingly holding the grip member in its retracted position during rocking movements of the arc piece, and the grip member having an operating exten-

sion extending radially to a point removed from the arc piece, said extension adapted to be pressed by the thrusting means to cause binding of the grip member on the arc piece and mutual rocking of grip member and arc piece for retraction of the welt guide.

4. In a welt sewing machine having means for feeding the work and for stitching the welt thereto, a welt guide mounted for movement transversely of the feed, and means for causing the retraction of the welt guide from the work in each stitch cycle, comprising a rock member actuating the welt guide, an arc piece rocking with said rock member, a grip member slidably engaging both internally and externally with said arc piece, and having an operating extension, and timed means for pressing said extension to cause the grip member to grip the arc piece and rock it, thereby to retract the welt guide in each

5. A machine as in claim 4 and wherein the grip member extension extends toward the axis of rocking, and the means for pressing it consists in a concentric member rotatable on said axis with a thrusting part normally inoperative but adapted to be rotated to contact the extension for gripping and rocking purposes.

In testimony whereof, I have affixed my signature hereto.
